Chicago, Ill., a corporation of Illinois

Filed May 6, 1969, Ser. No. 17,031

Term of patent 14 years

Int. Cl. D23—02

U.S. Cl. D23—58

FIG. 1

FIG. 2

FIG. 3

FIG. 1 is a top plan view of a sink showing my new design;

FIG. 2 is a front elevational view thereof; and

FIG. 3 is a perspective view thereof.

The characteristic feature of my invention resides in the particular configuration of the gradually sloped front corner of the sink as shown in FIGS. 1 and 3.

I claim:

The ornamental design for a sink, as shown and described.
